(57) **CLAIM**

The ornamental design for a receptacle, as shown and described.

DESCRIPTION

FIG. 1 is a top, front, left perspective view showing a first embodiment of my new design with the cover portion, having an arched top plate, and base portion coupled together;

FIG. 2 is a top, front, right perspective thereof;

FIG. 3 is front view thereof;

FIG. 4 is a back view thereof;

FIG. 5 is an inside view of the cover portion thereof;

FIG. 6 is an inside view of the base portion thereof;

FIG. 7 is an inside view of the base portion thereof having a bottle retained in the receptacle;

FIG. 8 is left side elevation view thereof;

FIG. 9 is right side elevation view thereof;

FIG. 10 is a right side elevation view of the cover portion thereof;

FIG. 11 is a right side elevation view of the base portion thereof;

FIG. 12 is a top plan view thereof;

FIG. 13 is a bottom plan view thereof;

FIG. 14 is a top, right, perspective view of the inside of the cover portion thereof;

FIG. 15 is a top, right, perspective view of the inside of the base portion thereof; and

FIG. 16 is a top, front, left perspective view showing a second embodiment of my new design with the cover portion, having a flat top plate, and base portion coupled together;

FIG. 17 is a top, front, right perspective thereof;

FIG. 18 is front view thereof;

FIG. 19 is a back view thereof;

FIG. 20 is an inside view of the cover portion thereof;

FIG. 21 is an inside view of the base portion thereof;

FIG. 22 is an inside view of the base portion thereof having a bottle retained in the receptacle;

FIG. 23 is left side elevation view thereof;

FIG. 24 is right side elevation view thereof;

FIG. 25 is a right side elevation view of the cover portion thereof;

(Continued)

FIG. 26 is a right side elevation view of the base portion thereof;

FIG. 27 is a top plan view thereof;

FIG. 28 is a bottom plan view thereof;

FIG. 29 is a top, right, perspective view of the inside of the cover portion thereof; and,

FIG. 30 is a top, right, perspective view of the inside of the base portion thereof.

The equal-length broken lines in the drawings depict portions of the receptacle that form no part of the claimed design.

The dash-dot broken line in FIG. 7 and FIG. 22 depicts environmental matter and forms no part of the claimed design.

1 Claim, 14 Drawing Sheets
